UNITED STATES PATENT OFFICE

ALFRED J. STECKER, OF ORCHARD LAKE, MICHIGAN

CARD DEALING MACHINE

Application filed October 8, 1930. Serial No. 437,270.

The present invention pertains to a novel machine for dealing out playing cards whereby to avoid the process of manual dealing that is now practiced.

As already suggested, one of the objects of the invention is to do away with the effort entailed in the manual dealing of cards. Another object is to remove the possibility of dishonest dealing, since the machine deals cut the cards in succession from the top of the pack placed therein.

The machine has four discharge slots and is positioned on the playing table in such a manner that the slots face the players. In the operation of the machine, the cards are issued successively through the slots and hence successively to the players.

The invention further embodies an automatic deal indicator and an automatic stop. The deal indicator is geared to the dealing mechanism in such a manner as to advance from one station to the next in the course of a complete deal. The automatic stop locks the mechanism after the last card has been delivered, so that the machine cannot be damaged by operation while empty and the deal indicator cannot be thrown out of register.

The invention is fully disclosed by way of example in the following description and in the accompanying drawings, in which—

Figure 1 is a plan view of the device with the cover broken away;

Fig. 2 is a longitudinal section thereof;

Fig. 3 is a transverse section on the line 3—3 of Figure 2;

Fig. 4 is a vertical longitudinal section on the line 4—4 of Figure 1;

Fig. 5 is an end elevation partly in section;

Fig. 6 is a fragmentary longitudinal section showing the cards bent on an axis lengthwise thereof;

Fig. 7 is a corresponding section on the line 7—7 of Figure 6;

Fig. 8 is a detail section on the line 8—8 of Figure 1;

Fig. 9 is a detail section on the line 9—9 of Figure 1; and

Fig. 10 is a detail perspective view.

Reference to these views will now be made by use of like characters which are employed

to designate corresponding parts throughout.

The device is built upon a base 1 formed with a wall 2 positioned inwardly of the edge of the base. To this wall is secured a top plate 3 by means of screws 4 as may be seen in Figure 7. The plate is formed with a central boss 5 in which is fixed a stud 6. Surrounding the stud and resting on the boss is a large worm gear 7 serving a purpose which will presently be described. Upon the gear 7 is mounted a sprocket wheel 8 in contact therewith and held in frictional engagement therewith by means of a dished spring plate 9 bearing on the sprocket wheel and held under tension against the same by means of a screw 10 threaded into the stud 6.

Upon the top plate 3 are formed pairs of aligned bearings 11 near each edge for the purpose of shifting shafts 12 and 13 along the longitudinal and transverse edges respectively of the top plate. The shafts are geared together at diagonally opposite corners by means of meshing bevel pinions 14 at the ends thereof. On each shaft 12 is secured a worm 15 meshing with the large gear 7 as shown in Figure 1.

A bridge 16 is mounted on the top plate 3 adjacent the gear 7 and preferably between the gear and one of the shafts 13. The object of this member is to retain a fixed stud 17, and the member is made in the form of a bridge to avoid interfering with certain structure therebeneath as will presently appear. Upon the stud is rotatably mounted a sprocket pinion 18 in the same plane with the sprocket gear 8 and operatively connected thereto by a sprocket chain 19 passed over both members. On the stud is also mounted the hub 20 of an operating handle or crank 21. The hub 20 has a one-way clutch connection 22 to the member 18 in order that the latter may be driven in only one direction on turning the crank 21 in the proper direction. It will not be apparent that such turning of the handle imparts a rotary motion to the sprocket wheel 8 and thence to the large gear 7, although the latter members will slip, due to the frictional engagement therebetween, if there is any obstruction to the operation of the machine. The appa-

ratus is constructed to function when the crank 21 and gear 7 are turned in clockwise direction, as may be seen by examination of the clutch 22 in Figure 2.

5 Within the confines of the wall 2 is disposed a slidable bottom plate 24 resting on crossed springs 25 disposed between it and the base 1. The member 24 is designed to support a pack of cards 26, and the tendency of the springs 25 is to move the cards upwardly towards the top plate 3.

The cards are inserted by manipulation of one of the lengthwise portions of the wall 2 which is constructed in the nature of a door 15 27 attached to the base by hinges 28 as may be seen in Figures 3 and 4. The apparatus is enclosed in a stamped cover 29 secured to the base, and the cover has an opening 30 at the door 27 for access thereto.

29 The cover plate 3 is formed with built up guideways 31 extending from the boss 5 perpendicularly towards the shafts 12 and 13 as may be seen more clearly in Figures 1, 9 and 10. In the guide-ways are mounted 25 slides 32 adapted to expel a card from the top of the pack 26 when moved towards the center of the machine as will presently appear. Each of the transverse slides is formed with a longitudinal slot 32' to accommodate 30 the superposed pinion 15 as shown in Figure 9. The outer end of each guide carries a pair of pivotally supported dogs 33 with projecting shoulders 34 (Figure 2) adapted to hang over the edge of the upper card.

35 The inner end of each slide 32 is equipped with a roller 35, and the lower face of the gear 7 is formed with a cam 36 adapted to engage the rollers successively, draw them inwardly, and thus cause the dogs of each slide 40 to move the top card towards a slot 37 in the opposite side of the cover 29. The shafts 12 and 13 carry pairs of rollers 38 beneath which are provided cooperating roller shafts 39 journaled on the wall 2. The aforementioned movement of the slides is sufficient to 45 insert the top card between the rollers which are so spaced as to exert a tractive pressure on the opposite faces of the card. Since the shafts 12 and 13 are turned by actuation of the crank 21, a card delivered to the rollers 50 will be moved through the adjacent slot 37 if the turning of the crank is continued.

The lower face of the gear 7 is further 55 formed with a retracting cam 40 positioned behind the cam 36 with respect to a clockwise direction of rotation and adapted to engage the rollers 35 successively after they have been drawn towards the center by the cam 36 and to return them to the position 60 where the dogs thereof lie at the edge of the pack of cards. Prior to being operated again, each pair of dogs must remain idle while cards are expelled by the other three slides 65 and in three different directions, in one of 70 which directions a card must be passed be-

neath the pair of dogs under consideration. Assuming that this pair is that shown at the righthand end of Figure 2, it will be seen that the dogs must be removed from the path of the uppermost card when the latter is to be expelled through the slot 37 at the right-hand end of the cover. The dogs under consideration are capable of further outward movement beyond the position shown at the righthand end of Figure 2, as may be seen 75 by the position of the cam 36 in Figure 1. The dogs move in slots 41 at the edges of the plate 3, and the outer wall of each slot is sloped or beveled downwardly towards the center of the plate as indicated by the numeral 42. The dogs carry lateral pins 43 (Figure 10) which ride on the sloping ends 42 during the aforementioned outward movement of the slides, whereby the dogs are successively raised out of the path of the upper 80 card as illustrated at the lefthand end of Figure 2.

The guides 31 which are belt up from the plate 3 have their outer extremities beveled to slope downwardly towards the center of the device as indicated by the numeral 44 in Figure 10. When the dogs are raised to a clear position, the pins 43 thereof lie adjacent the ends 44. Thus, when a slide positioned as shown at the lefthand end of 90 Figure 2 is initially drawn inwardly by the expelling cam 40, the pins 43 first ride along the ends 44 whereby the dogs are turned to an upright position so that the teeth 34 thereof overhang the edge of the upper card and are in position to propel the card on continued movement of the slide by the cam 40. 95

In order to enable proper dealing of the cards in the event that they have become bent 100 in use, gate members 45 are slidably mounted on each of the four parts of the wall 2 and are retained in a sliding position by guide plates 46 secured to the wall 2. With the exception of the gate on the door member 27, the gates are normally moved upwardly by coil springs 47 resting on the base 1 and bearing against sockets 48 formed at the lower edge of the gates. The gate 45' on the door 105 27 has at its lower end a stud 49 engaged by a flat or wire spring 50, the ends of which are mounted on studs 51 fixed to the door. The spring 50 is so tensioned as to exert an upward force on the gate. This construction is illustrated in Figure 4 which also shows the means for retaining the door in closed position. Latch bolts 52 are slidably supported in ears 53 formed on the door and have their outer ends adapted for reception in slots 54 formed in the parts of the wall 2 at the ends 110 of the door. The inner ends of the members 52 are reduced as at 55 and slidably received in a bracket 56 secured to the door. These ends are surrounded by springs 57 which bear against the bracket, thereby tending to move the bolts 52 into the slots 54. The bolts are 115 120 125

pulled together and drawn out of the slots for opening the door, by pressing on tabs 58 formed on the members 52 near the reduced ends 55 thereof.

With reference again to the gates 45, the lower face of the top plate 3 has flat springs 60 secured thereto as shown more clearly in Figure 6. The free end of each such spring carries a spacing member 61 adapted to rest upon one of the gates 45.

The springs 60 are positioned at the mid points of the edges of the cards as may be seen in Figures 4 and 7. The springs 60 are stronger than the springs 47 so that the final position of the gates is determined by the engagement of the springs 60 with the edges of the top card. When the pack of cards is spent, one pair of parallel edges will be lower than the other pair. When the dogs 33 are in elevated position at the lower edges, the gates 45 are depressed to the extent determined by the engagement of the springs 60 with the lower edges.

The dogs 33 at the higher edges of the pack, in swinging from the elevated to the lower or operative position shown at the righthand end of Figure 2, depress these edges and hold them in a depressed position due to the fact that the length of each dog from the pivot point to the card-engaging shoulder thereof is sufficient to take up the difference in height between the higher and lower edges. In other words, the points on which the dogs rest when in operative position are depressed to substantially the level of the lower edges where engaged by the springs 60. The tooth 34 of each dog, however, is only of such length as to overhang the top card, so that when the dog is propelled, it expels only the top card.

An automatic deal indicator is incorporated in the device and is operated from the crank 21. The indicator proper comprises a ratchet 65 journaled on a stud 66 formed on the lower face of the cover 29 and held by a screw 67 and spring 68. The face of the ratchet has a flange 69 bearing the characters N, E, S, W. These characters indicate the positions at the playing table and are visible one at a time as they pass beneath an opening 70 in the top of the cover 29.

An arm 71 is pivoted to the lower side of the cover and is formed at its free end with a tooth 72 engageable by an abutment 73 formed on the gear 7. To an intermediate point of the arm 71 is pivoted a pawl 74 adapted to actuate the ratchet when the arm 71 is swung towards the ratchet and to move idly over the ratchet in the opposite direction. The rear end of the pawl is joined by a spring 75 to a fixed point on the cover 29 and thereby tends to draw the members 71 and 74 away from the ratchet and to bring the tooth 72 into the path of the member 73 to be engaged thereby.

The ratchet is advanced one tooth with

each revolution of the gear 7 or with the dealing of every fourth card. There are thirteen teeth on the ratchet between stations. The dealing out of a conventional pack of fifty-two cards therefore advances the ratchet 70 thirteen teeth or one station.

The machine also has an automatic stop device to avoid any possible destructive result by turning the crank 21 after all the cards have been dealt out and also to avoid overrunning of the deal indicator. A boss 76 is formed on the top plate 3 as shown in Figure 8 and has a pin 77 slidably mounted therein. The pin has a reduced and rounded lower end 78 resting upon the pack of cards 80 and adapted to drop into an aperture 79 in the bottom plate 24 when all the cards have been dispensed. An arm 80 extends laterally from the pin 77 through a slot 81 in the boss and carries at its free end a circular head 82 adapted to drop into an opening 83 in the gear 7 when the member 78 drops into the aperture 79. The hole 83 is so positioned on the gear 7 that it registers with the head 82 when any multiple of four cards remains between the plates 3 and 24, so that there will also be a registration immediately on the delivery of the last card. At this time, the pin 77 descends by its own weight and the head 82 drops into the opening 83 to lock the gear so that the machine can no longer be operated. The opening 83 is preferably elongated as shown in Figure 1 to facilitate entrance of the head 82 therein.

The plate 24 and base 1 carry cooperating angular fingers 85 adapted to interlock as shown in Figure 5. Normally, however, the fingers are disengaged so that the member 24 may move. When a deck of cards is to be inserted at the door 27, the fingers are brought into interlocking engagement which is permitted by the looseness of the member 24 within the confines of the wall 2. The plate 24 is thus held in a depressed position against the tension of the springs 25 while a new deck is being inserted, after which the fingers may be released from each other by merely shifting the plate 24.

The device is operated by merely turning the handle 21 continuously in clockwise direction. By the mechanism already described in detail, the cards are delivered in succession from the slots 32 at the four sides of the device. The machine is positioned on the playing table so that each slot faces one of the players. When the entire pack of cards has been distributed, the machine is locked against further motion by the head 82, and the next dealer is indicated at the opening 70 as also previously described.

Although a specific embodiment of the invention has been illustrated and described, it will be understood that various alterations in the details of construction may be made without departing from the scope of the in-

vention, as indicated by the appended claims.

What I claim is:—

1. A card dealing machine comprising a receptacle having lateral openings, ejecting members adapted to move cards towards said openings, a main gear, a cam on said gear adapted to operate said ejecting members successively, and means for returning said members to initial position.
2. A card dealing machine comprising a receptacle having lateral openings, ejecting members adapted to move cards towards said openings, a main gear, an expelling cam on said gear adapted to operate said members successively, and a retracting cam on said gear adapted to return said members successively to initial position.
3. A card dealing machine comprising a receptacle having lateral openings, ejecting members adapted to move cards towards said openings, a main gear, a cam on said gear adapted to operate said ejecting members successively, means for returning said members to initial position, and a pair of rollers at each opening adapted to receive a card therebetween, said rollers being geared to said main gear, whereby to deliver the cards through said openings after receiving them from said ejecting members.
4. A card dealing machine comprising a receptacle having lateral openings, ejecting members adapted to move cards towards said openings, a main gear, an expelling cam on said gear adapted to operate said members successively, a retracting cam on said gear adapted to return said members successively to initial position, and a pair of rollers at each opening adapted to receive a card therebetween, said rollers being geared to said main gear, whereby to deliver the cards through said openings after receiving them from said ejecting members.
5. A card dealing machine comprising a receptacle having lateral openings, a fixed top plate and a floating bottom plate in said receptacle, spring means urging said bottom plate upwardly, ejecting members slidably mounted on said top plate and adapted to move cards towards said openings, a main gear, a cam on said gear adapted to operate said ejecting members successively, and means for returning said members to initial position.
6. A card dealing machine comprising a receptacle having lateral openings, a fixed top plate and a floating bottom plate in said receptacle, spring means urging said bottom plate upwardly, ejecting members slidably mounted on said top plate and adapted to move cards towards said openings, a main gear, a cam on said gear adapted to operate said ejecting members successively, means for returning said members to initial position, and a pair of rollers at each opening adapted to receive a card therebetween, said
- rollers being geared to said main gear, whereby to deliver the cards through said openings after receiving them from said ejecting members.
7. A card dealing machine comprising a receptacle having lateral openings, a fixed top plate and a floating bottom plate in said receptacle, spring means urging said bottom plate upwardly, slides mounted on said top plate and adapted to move towards said openings, dogs carried by said slides and adapted to engage the edges of the uppermost card on said bottom plate, a cam on said main gear adapted to accommodate said slides successively, and means for returning said slides to initial position.
8. A card dealing machine comprising a receptacle having lateral openings, a fixed top plate and a floating bottom plate in said receptacle, spring means urging said bottom plate upwardly, slides mounted on said top plate and adapted to move towards said openings, dogs carried by said slides and adapted to engage the edges of the uppermost card on said bottom plate, an expelling cam on said gear adapted to operate said slides successively, and a retracting cam on said gear adapted to return said slides successively to initial position.
9. A card dealing machine comprising a receptacle having lateral openings, a fixed top plate and a floating bottom plate in said receptacle, spring means urging said bottom plate upwardly, slides mounted on said top plate and adapted to move towards said openings, dogs carried by said slides and adapted to engage the edges of the uppermost card on said bottom plate, an expelling cam on said gear adapted to operate said slides successively, a retracting cam on said gear adapted to return said slides successively to initial position, means for lifting said dogs clear of said cards when in extreme retracted position and for returning said dogs into active engagement with the uppermost card at the commencement of the expelling movement of said slides.
10. A card dealing machine comprising a receptacle having lateral openings, ejecting members adapted to move cards towards said openings, a main gear, a cam on said gear adapted to operate said ejecting members successively, means for returning said members to initial position, and a deal indicator geared to said main gear in such ratio as to advance one station in the dealing of a deck of cards.
11. A card dealing machine comprising a receptacle having lateral openings, ejecting members adapted to move cards towards said openings, a main gear, a cam on said gear adapted to operate said ejecting members successively, means for returning said members to initial position, and a stop member carried by a fixed part of the device and

adapted to lock said bottom plate on removal of the last card therefrom.

12. A card dealing machine comprising a receptacle having lateral openings, an inner wall within said receptacle and adapted to confine a deck of cards, a top plate fixedly supported in said receptacle, ejecting members slidably mounted on said top plate and adapted to move cards towards said openings, a main gear, a cam on said gear adapted to operate said ejecting members successively, means for returning said members to initial position, spring supported gates slidably mounted on said inner wall, and spring pressed spacer members carried by the lower face of said top plate and bearing downwardly upon said gates.

13. A card dealing machine comprising a receptacle having lateral openings, a fixed top plate and a floating bottom plate in said receptacle, spring means urging said bottom plate upwardly, slides mounted on said top plate and adapted to move towards said openings, dogs carried by said slides and adapted to engage the edges of the uppermost card on said bottom plate, a cam on said main gear adapted to accommodate said slides successively, means for returning said slides to initial position, an inner wall within said receptacle beneath said top plate and adapted to confine a deck of cards, spring supported gates slidably mounted on said inner wall, and spring pressed spacer members carried by the lower face of said top plate and bearing downwardly upon said gates.

14. A card dealing machine comprising a receptacle having lateral openings, a fixed top plate and a floating bottom plate in said receptacle, spring means urging said bottom plate upwardly, slides mounted on said top plate and adapted to move towards said openings, dogs carried by said slides and adapted to engage the edges of the uppermost card on said bottom plate, a cam on said main gear adapted to accommodate said slides successively, means for returning said slides to initial position, and a pair of rollers at each opening adapted to receive a card therebetween, said rollers being geared to said main gear, whereby to deliver the cards through said openings after receiving them from said slides.

15. A card dealing machine comprising a receptacle having lateral openings, a fixed top plate and a floating bottom plate in said receptacle, spring means urging said bottom plate upwardly, slides mounted on said top plate and adapted to move towards said openings, dogs carried by said slides and adapted to engage the edges of the uppermost card on said bottom plate, a cam on said main gear adapted to accommodate said slides successively, means for returning said slides to initial position, an inner wall within said receptacle beneath said top plate and adapted to

confine a deck of cards, spring supported gates slidably mounted on said inner wall, spring pressed spacer members carried by the lower face of said top plate and bearing downwardly upon said gates, and a pair of rollers at each opening adapted to receive a card therebetween, said rollers being geared to said main gear, whereby to deliver the cards through said openings after receiving them from said slides.

16. A card dealing machine comprising a receptacle having lateral openings, a fixed top plate and a floating bottom plate in said receptacle, spring means urging said bottom plate upwardly, slides mounted on said top plate and adapted to move towards said openings, shouldered means carried by said slides and adapted to engage the edges of the uppermost card on said bottom plate, a cam on said main gear adapted to accommodate said slides successively, and means for returning said slides to initial position.

17. A card dealing machine comprising a receptacle having lateral openings, a fixed top plate and a floating bottom plate in said receptacle, spring means urging said bottom plate upwardly, slides mounted on said top plate and adapted to move towards said openings, dogs carried by said slides and having shoulders adapted to engage the edges of the uppermost card on said bottom plate, a cam on said main gear adapted to accommodate said slides successively, and means for returning said slides to initial position.

In testimony whereof I affix my signature.

ALFRED J. STECKER.
